United States Patent Office

Des. 198,054
Patented Apr. 21, 1964

198,054

BOTTLE

Alan B. Lowry, Canton, Mass., assignor to The Gillette Company, Boston, Mass., a corporation of Delaware

Filed Aug. 23, 1961, Ser. No. 66,463

Term of patent 14 years

(Cl. D58—8)

FIG. 1

FIG. 3

FIG. 1 is a view in elevation of a bottle, showing my new design,

FIG. 2 is a top plan view thereof, and

FIG. 3 is a cross-sectional view taken through the center of the closure.

I claim:

The ornamental design for a bottle, substantially as shown.
